DISPLAY RACK FOR BOOKS, MAGAZINES OR THE LIKE

Melvin Cohen, 150 Dayton Ave.,
Passaic, N.J. 07054

Filed Aug. 9, 1968, Ser. No. 13,077

Term of patent 14 years

Int. Cl. D6—01

U.S. Cl. D80—9

FIG. 1

FIG. 5

FIG. 2

FIG. 3

FIG. 4

FIG. 6

FIG. 1 is a front elevational view of a display rack for books, magazines or the like showing my new design;

FIG. 2 is a rear elevational view thereof;

FIG. 3 is a top plan view thereof;

FIG. 4 is a bottom plan view thereof;

FIG. 5 is a cross sectional view taken on line 5—5 of FIG. 1; and

FIG. 6 is an elevational view taken from one side thereof, the opposite side being a mirror image of the side shown.

The broken line showing of book shelves in FIG. 5 are for illustration only.

I claim:

The ornamental design for a display rack for books, magazines or the like, as shown and described.
